UNITED STATES PATENT OFFICE.

SAMUEL H. TACY, OF ELKINS PARK, PENNSYLVANIA, ASSIGNOR TO PRE-HEATED AIR COMPANY, OF PHILADELPHIA, PENNSYLVANIA, A CORPORATION OF DELAWARE.

PREHEATER-PLATE.

1,249,551.

Specification of Letters Patent. Patented Dec. 11, 1917.

Application filed February 16, 1912. Serial No. 678,078.

To all whom it may concern:

Be it known that I, SAMUEL H. TACY, a citizen of the United States, and a resident of Elkins Park, Pennsylvania, have invented a certain new and useful Preheater-Plate, of which the following is a specification.

The purpose of my invention is to provide a stove lid with pre-heating air passages 10 reversely directed in straight lines and in which the air comes in contact with the outer side wall of the plate at every turn.

A further purpose of my invention is to introduce the air at one edge of the plate, to 15 pre-heat it and to deliver it at the opposite edge of the plate in a diagonal direction.

A further purpose of my invention is to vary the width of pre-heating passages from one side of plate to the other so that the air 20 shall have additional space in approximate proportion to the increased volume as its temperature increases.

Further purposes will appear from the specification and the claims appended 25 thereto.

I have preferred to illustrate my invention by forms thereof which are known to be practical, effective and inexpensive and which at the same time well illustrate the 30 principles of my invention.

Figure 1 is a top plan view of a plate embodying one form of my invention.

Fig. 2 is a side elevation partly broken 35 of the structure shown in Fig. 1.

Fig. 3 is a side elevation of another form 40 of my invention.

The top plate 5, in both of the forms illustrated, is provided with an inlet opening 6 located close to the edge of the plate and 45 shown as controlled by a controller 7 described and claimed by me in another application, co-pending herewith. The controller is here shown as pivoted. The controller is effective as a cam closure for the opening 6,

in that the outer wall of the opening 8 is eccentrically formed to gradually close the opening 6 with counter-clockwise movement. The controller carries indicator 9, and moves 50 within raised guard walls 10, which are interrupted at 11 to allow air passage, free from possible accidental closure by utensils placed upon the lid.

I prefer to make the bottom structure separable from the top plate 5 and show it in

Fig. 2 as comprising a bottom wall 12 approximately parallel to the top plate and connecting therewith by outer approximately cylindrical side wall 13 and partition walls 14 to 20 so as to provide passages beginning at the inlet opening 6 and discharging preferably diagonally through a number of holes 21 placed about a suitable part of the circumference.

I have shown the two parts of the plate as retained by suitable means, such as 65 stove bolts 22. For the purpose of relieving the retaining means 22 from side strain, I have supported the wall 13 laterally, preferably placing it within a correspondingly shaped ring 23.

I have shown the wall 18 as shortened to give room for any usual form of lifter recess 24.

Since the volume of the air increases with the increase of temperature, and in order 75 to provide cross sectional area for the passages approximately proportionate thereto, I have spaced the partition walls 14 to 20 by increasing intervals, intended to correspond to the increase of volume with the 80 normal condition of the fire when the plate is used. Obviously, this will vary somewhat with the position which the plate is intended to occupy. Ordinarily the plate will be located close to the smoke flue and at a distance from the fire box.

In the form shown in Fig. 3 I have proportioned the cross sectional areas of the successive passages in a different way, by sloping the bottom plate 12' away from the top 90 plate from the inlet to the discharge sides, thus giving additional cross sectional area as the discharge opening is approached. Obviously, either or both of these methods of proportioning the cross section can be used 95 at will and the change of section can be regular or irregular, as conditions of use or convenience may dictate.

The diagonal direction of discharge of pre-heated air is desirable for some purposes, 100 as it gives a distribution of the air which proves particularly effective when this lid is placed near to the fire box. The effect is improved by locating the openings about the approximate arc of a circle as the pre-heated air is fed along what might be called a frustum of a cone sector.

It will be evident that the air in each of

the passages is exposed to the heat of the interior of the stove through the bottom wall at all times and that it is additionally exposed to this outside wall heating effect throughout one entire side of the passage at the inlet, for a short distance at the end of each passage during each change of direction, and throughout the outside wall at the point of discharge, giving highly advantageous outside wall heating effect.

In the form shown in Fig. 3 the heat from the bottom wall is relatively increased in the passages nearest to the inlet by the relative shallowness of these passages.

It will be evident that in the form shown in Fig. 3, the conoidal form of the wall 25 greatly reduces the disparity in heights between the walls at 26 and at 27 and that this beveling may be as great in height at any point and extend as far circumferentially, as may be desired to facilitate the placing of the plate by the taper thus provided.

Having thus described my invention, what

I claim as new and desire to secure by Letters Patent is:

1. In a stove lid, a top plate provided with an inlet opening, a bottom plate at an angle to said top plate, parallel partitions forming air passages therebetween and an outer side wall of generally cylindrical shape tapered at the part of greater elemental length and there apertured for air discharge.

2. In a stove lid, a top plate provided with an inlet opening, a bottom plate sloping with respect to the top plate, being nearest to it in proximity to the inlet opening, substantially parallel partitions forming air passages between the plates of different cross section, growing larger as the outlet is approached and an outer wall of generally cylindrical shape apertured to provide outlet in proximity to the point of greatest spacing between the top and bottom plates.

SAMUEL H. TACY.
